DIRIGIBLE SEARCHLIGHT

Arthur P. Sauer, Fairfield, Conn., assignor to
The Kilborn-Sauer Company, Fairfield, Conn.,
a corporation of Connecticut

Application May 29, 1948, Serial No. 30,127

3 Claims. (Cl. 240—61.13)

1

The present invention relates to a dirigible searchlight, particularly of the type for marine use adapted to be mounted upon the roof of a boat cabin, or the like, for directional and angular control from a point within the cabin remote from the search-light. An object of the invention is to provide a search-light structure having improved mechanism for turning the search-light about horizontal and vertical axes, such mechanism being designed to occupy a relatively small space, and being at the same time capable of obtaining a relatively great mechanical advantage so that the searchlight may be quickly actuated with comparatively little effort. A further object is to provide a search-light structure in which the operating parts are completely enclosed, so that they are effectually protected against the entrance of water, salt spray, and other deteriorating elements.

With the above and other objects in view an embodiment of the invention is shown in the accompanying drawings, and this embodiment will be hereinafter more fully described with reference thereto, and the invention will be finally pointed out in the claims.

In the drawings:

Fig. 1 is a side elevation of a dirigible searchlight, according to the illustrated exemplary embodiment of the invention.

Fig. 2 is a vertical sectional view thereof taken along the line 2—2 of Fig. 3.

Fig. 3 is a vertical sectional view taken along the line 3—3 of Fig. 2.

Fig. 4 is a horizontal sectional view taken along the line 4—4 of Fig. 2.

Fig. 5 is a horizontal sectional view taken along the line 5—5 of Fig. 2.

Similar reference characters indicate corresponding parts throughout the several figures of the drawings.

Referring to the drawings, the dirigible searchlight, according to the illustrated exemplary embodiment of the invention, comprises a mounting base 10 of hollow form having a closure plate 11 secured in its lower end by brazing or the like, and provided with a central vertically disposed tubular bearing 12 secured by swaging its upper and lower shouldered ends respectively within a central opening 13, in the dished portion 14 of the upper wall, and a central opening 15, in an upwardly recessed portion 11a of the closure plate 11.

Rotatably mounted upon the base 10 is a head member 16 having an annular rib 17 at its lower side engaging the annular bearing surface 18 of

2

the upper wall of the base member, a vertically disposed tubular sleeve 19 being fixed centrally within the head 16 and projecting above and below it with its downwardly projecting portion having rotatable bearing in the tubular bearing 12. A retaining nut 20 is screwed upon the lower end of the sleeve 19 in opposed relation to the lower end of the bearing 12. The sleeve 19 is rigidly secured to the head member 16 in any suitable manner, preferably by casting the head member 16 about the sleeve member 19.

A vertical slot 21 is provided in the upper portion of the sleeve 19, extending from the base of a recess 22 in the upper side of the head member 16 to the upper end of the tube. A plunger shaft 23 is slideably engaged in the tube 19, and is provided at its upper end with a horizontally projecting arm 24 rigidly fixed thereto and projecting through the slot 21, this arm performing the dual function of imparting rotation to the head 16 to control the directional position of the search-light upon rotary movement being applied to the plunger 23, and of operating mechanism, presently to be more fully described, to control the angular position of the search-light upon vertical movement applied to the plunger 23.

For the purpose of imparting rotary and vertical movement to the plunger 23 there is fixedly secured to its lower end by means of a pin 25 a flexible rod 26 extending through a flexible housing tube 27, and provided at its remote end with an operating handle 28, the housing tube being secured at its upper end by being screwed into an internally threaded flanged collar 29 secured by screws 30 to the underside of the closure plate 11. By turning the handle 28, the plunger 23 and the head 16 are rotated, and by pushing or pulling the handle, the plunger is vertically moved up or down.

The base 10 is adapted to be secured by bolts 31 to the boat top, or the like, 32, a passage 33 being provided in the boat top through which the housing tube 27 extends.

Upon the upper side of the head 16 there is mounted a housing member comprising two similar half sections 34—34 separable along the central vertical plane of the housing and each provided with a base flange 35 secured by screw 36 to the head 16. A bearing bushing 37 is provided in each of the half-sections 34, in which is journaled a shaft 38, and having secured upon its projecting ends by pins 39 a pair of lamp supporting lugs 40—40 secured by rivets or the like, 41, to the lamp casing 42. The upper end of the housing member is of circumferential curved

55

form concentric to the shaft 38 and projects into an opening 43 in the casing between the lugs 40 to permit pivotal angular adjustment of the lamp through rotation of the shaft 38.

A lever 44 is pivotally mounted intermediate its ends by means of a pivot screw 45 upon the side of the sleeve 19 adjacent its upper end, and is pivotally connected at one end by a link 46 to the outer end of the arm 24, its other end being pivotally connected by a link 47 to the outer end of an arm 48 having an integral hub 49 at its inner end secured upon the shaft 38 by means of a pin 50. Downward movement of the plunger 23 to the position indicated by the dash lines in Fig. 2 swings the lever 24 in counter-clockwise direction and through the link 47 swings the arm 48 upwardly, thus rotating the shaft 38 to swing the lamp casing downwardly. Upward movement of the plunger 23 to the position indicated by the dotted lines swings the lever 44 in clockwise direction and through the lever 47 swings the arm 48 downwardly, thus rotating the shaft 38 to swing the lamp casing upwardly. The arrangement is such that the mechanical advantage of the levers is obtained within a relatively compact space completely enclosed within the housing member 33.

The electrical conductor wire 51 extends from the lamp through an opening 52 in the upper end of the housing member 33, and through the housing member to a resiliently mounted stemmed contact button 53, engaged in a flanged sleeve 54 slideably mounted in an insulating tube 55 set into a pocket 56 in the head member 46, a passage 57 being provided at the upper end of said pocket through which the conductor 51 extends. A spring 58 is interposed between the flanged sleeve 53 and the insulating tube 55 and presses the contact button into engagement with a circular contact ring 59 mounted upon an insulating ring 60 seated in the dished upper wall portion 14 of the base member 40. The rings 59 and 60 are secured by means of screws 61 engaged upwardly through flanged insulating bushings 62 and screwed into the contact ring 59. One of the screws 61 serves as a binding post for a conductor wire 63 adapted to be connected to a suitable source of electric energy, this wire extending through a hole 64 in the closure plate 41 of the base 40 and through a passage 65 in the roof 32.

I have illustrated and described a preferred and satisfactory embodiment of the invention, but it will be understood that changes may be made therein within the spirit and scope thereof as defined in the appended claims.

What is claimed is:

1. In a dirigible search-light, a mounting base member adapted to be fixed to a supporting structure and having a central vertical bearing, a head member mounted on said base member having a central vertically disposed tube fixed thereto and extending above and below it and having its lower end engaged in said bearing of said base member for rotation about a vertical axis, said tube having a vertical slot in one side thereof extending along its upwardly projecting portion above said head member, a plunger engaged in said tube for vertical movement therein having a fixed arm extending laterally through said slot whereby rotation of said plunger imparts rotation to said head member, a housing member secured upon the upper side of said head member, a

transverse shaft rotatably mounted in said housing member, a lamp casing having supporting means fixed to said shaft, a lever arm secured to said shaft within said housing, and a lever system within said housing connected between said fixed arm of said plunger and said lever arm arranged to impart rotation to said shaft through vertical movement of said plunger.

2. In a dirigible search-light, a mounting base member adapted to be fixed to a supporting structure and having a central vertical bearing, a head member mounted on said base member having a central vertically disposed tube fixed thereto and extending above and below it and having its lower end engaged in said bearing of said base member for rotation about a vertical axis, said tube having a vertical slot in one side thereof extending along its upwardly projecting portion above said head member, a plunger engaged in said tube for vertical movement therein having a fixed arm extending laterally through said slot whereby rotation of said plunger imparts rotation to said head member, a housing member secured upon the upper side of said head member, a transverse shaft mounted in said housing member, a lamp casing having supporting means fixed to said shaft, a lever arm secured to said shaft within said housing, a lever pivotally mounted between its ends within said housing member, a link connecting one end of said lever to said fixed arm of said plunger, and a second link connecting the other end of said lever to said lever arm, whereby vertical movement of said plunger imparts rotation to said shaft.

3. In a dirigible search-light, a mounting base member adapted to be fixed to a supporting structure and having a central vertical bearing, a head member mounted on said base member having a central vertically disposed tube fixed thereto and extending below it and having its lower end engaged in said bearing of said base member for rotation about a vertical axis, a plunger engaged in said tube for vertical movement, means keying said plunger to said tube whereby rotation of said plunger imparts rotation to said head member, a flexible shaft extending upwardly through said tube and fixed to said plunger for imparting rotary and vertical movement thereto, a housing member secured upon the upper side of said head member, a transverse shaft rotatably mounted in said housing member, a lamp casing having supporting means fixed to said shaft, a lever arm secured to said shaft within said housing, and a lever system within said housing connected between said plunger and said lever arm arranged to impart rotation to said shaft through vertical movement of said plunger.
